UNITED STATES PATENT OFFICE.

CHARLES E. BUELL, OF NEW HAVEN, CONNECTICUT.

COMBINED CALL-BELL AND FIRE-ALARM SYSTEM.

SPECIFICATION forming part of Letters Patent No. 286,529, dated October 9, 1883.

Application filed January 31, 1883. (No model.)

To all whom it may concern:

Be it known that I, CHARLES E. BUELL, of the city and county of New Haven, State of Connecticut, have invented Improvements in 5 Combined Call-Bell and Fire-Alarm Systems, of which the following is a specification.

My invention relates to signaling to and from rooms in a hotel, factory, or other building, and other analogous uses; and it consists 10 in the combination of a wire or wires connecting the several rooms of a building with an office, devices at each room for transmitting signals to the office, receiving apparatus at the office for definitely determining from which 15 room signals are sent, an alarm-bell for each room, and transmitting devices at said office for sending alarm-signals to the several rooms simultaneously, the whole arranged and operating substantially as hereinafter set forth, 20 whereby the guests and occupants in hotels and buildings can signal to the office and the office can give instant alarm-signals to all occupants in event of fire. My invention consists in other combinations and sub-combinations, 25 which will be hereinafter described.

Figures 1, 2, and 3 show arrangement of circuits and apparatus for carrying out my invention. Figs. 4 and 5 are detailed parts of apparatus for carrying out my invention.

Fig. 1 shows an annunciator, A, and bell G, at an office, with the wires 1, 2, and 3 connected, through the annunciator A, in the usual manner, and through the bell G and a suitable battery to earth or other return-circuit at g.

The wires 1, 2, and 3 lead to separate apartments, and are connected to the gas fixture of their respective apartment, and each provided with an open-circuit push-button key, P B, of well-known construction and operation. In 40 each room I place a call-bell, G', of ordinary construction, preferably a continuous vibrating bell. The electro-magnet of said call-bell G' is included in a branch wire, b, that connects between the wire 1, 2, or 3, as the case 45 may be, and the wire 4 in dotted lines, the wire 4 being a wire common to the several rooms and normally terminating at the office without a charging-battery, but in such relation to the switch S that, when occasion requires, the bat-

tery commonly employed to operate the annunciator A and bell G can be connected to wire 4, making operative the several bells in the various apartments for giving an alarm, the current from the battery dividing through the magnets of the several bells G' and being 50 returned over the gas-pipes. A separate battery may be employed, and any other return-circuit be used in place of the gas-pipes to operate outgoing signals from the office. I have shown the bells G' in a branch-wire, b, so disposed as not to be made operative by the closing of the push-button key P B, but adapted to be made operative by the same battery and return-circuit used for signaling from the 55 rooms to the office. At the terminal of the branch b in each room I place a thermostat, T, adapted to act by heat, to transmit, automatically, the signal from the apartment in which it is placed that would be transmitted by the push-button key of such apartment. The preferred form of thermostat is to be hereinafter 60 described. By arranging the said thermostat in such relation to the call-bell G' of its respective apartment, and with the push-button key at that apartment open, the bell G' is rung 65 over the wire 1, 2, or 3, as the case may be, giving additional security by an earlier warning than the general alarm from the office to the occupants of that and of adjacent apartments within sound of said disturbed bell, and 70 at the same time making operative the bell G and annunciator A at the office by the action of the thermostat T.

Fig. 2 shows a modification of the system shown in Fig. 1 and described. A represents 85 a register of any well-known construction for receiving and recording signals, as employed in district telegraphs. This register is placed in the office of a hotel or factory, and its electro-magnet E M included in the 90 wire W, which is normally charged, and which extends to the various apartments of the building, and is returned over the gas-pipes or other return-circuit. A call-bell, G, is also placed at the office, and its electro-magnet included in the wire W. At each apartment a signal-box, B, and call-bell G' are included 95 in the wire W. The signal-box is adapted to

transmit a definite number of signals for each apartment in a well-known way, the call-bell G' at each of the apartments being constructed and adjusted to remain inoperative with the currents of normal strength, and is preferably a continuous vibrating call-bell of ordinary form. When it is desired to transmit a call from either room to the office, the handle X of the signal-box B at such room is turned from its position of rest and the clock-work in the box B wound up, and in running down makes operative the circuit leading to the office a definite number of times, producing a recorded signal upon the register A at the office, and an audible signal upon the tap-bell G , also at the office. The box B is, preferably, normally partially wound up, and prevented from running down by the stop n , which projects from the front of the box to obstruct the turning of the handle X , and said stop is of or secured by an easily-fusible metal that will melt by an abnormal temperature, and thus release the partly-wound-up mechanism of the box B , sending a signal to the office by the action of heat. A resistance, R , is shown at the office for controlling the force on the wire W . The boxes B are adapted to be operated by hand to turn in signals to the office, and to be automatically started by the action of heat. When an alarm is to be sent to the several rooms, the switch S is turned to connect with the branch wire h , cutting out the resistance R and electro-magnet $E M$, and, by augmenting the force in wire W , making operative the several call-bells G' and sounding an alarm simultaneously in all the rooms.

Fig. 3 shows the wire W with the electro-magnet of the register and the call-bell G at the office, the electro-magnet $E M$ being adjusted to be normally with its armature retracted, a resistance, R , being in a remote portion of the circuit-wire W , the signal-boxes B at each room being adapted to put on and take off a ground or branch wire, g^2 , when running down, short-circuiting the battery and making operative the receiving apparatus at the office. An electro-magnet with polarized armature $P R$ is included in a remote point of wire W from the office, and adapted to cut out the resistance R , when made operative, by a reversal of the currents on wire W , the call-bells G' being adjusted to be operative when the force in the wire W is greater than that employed to send signals from the rooms to the office. To send alarm-signals to all the rooms simultaneously, the switch S is turned to connect wire W with a battery of opposite polarity from the battery ordinarily used. This change of current cuts out the resistance R by the action of electro-magnet $P R$, and the alarm-bells G' sound an alarm, the cutting out of the resistance R having the same effect as increasing battery. The register-magnet $E M$ may be placed in a local circuit and made operative by a relay in wire W in the manner used by district telegraphs.

Fig. 5 represents a continuously-acting "circuit-changer," so called, which is adapted to send rapidly-succeeding pulsations to the different rooms to make operative tap-bells in place of vibrating gongs, as $G' G'$. The operation is as follows: When the switch S at the office is turned to connect the battery to branch wire h' , the current from the battery passes by spring e over the armature of the electro-magnet V , and through the helices of said electro-magnet, which then attracts said armature and brings spring e in contact with stop a , discontinuing the current through the electro-magnet helices V , and sending the current of the battery to the tap-bells in the several rooms. The armature is immediately retracted into contact with spring e , and the operation described is rapidly repeated. Thus, in place of continuously-acting or self-acting gongs, tap-bells may be rapidly sounded in the rooms. The form of automatic vibrator described in Letters Patent No. 249,296 may be used in place of that shown in Fig. 5 and described.

Fig. 4 is a plan view of a preferred form of thermostat to be employed with the apparatus shown in Fig. 1. It consists of a spring, K , secured to a metal shell that is adapted to be screwed to the wall or ceiling of a room. The spring k is retracted against the stop i and soldered thereto by an easily-fusible solder, so as to come in contact with the insulated plate j when unsoldered by an increase of temperature, and by such contact to close the branch wire b and wire 1, 2, or 3, making operative the receiving apparatus at the office over the wire 1, 2, or 3, as ease may be.

Other forms of circuit-closing thermostats may be employed in place of the one described without departing from my invention, and a thermostat combined with a push-button key may be used, as shown in another application.

In Fig. 1 the wire 4 (shown in dotted lines) may be a wire or a water, steam, or other pipe or conductor, as shown and described in Letters Patent No. 262,887.

The several rooms can be called by separate keys or successively, as shown in my Letters Patent No. 262,887; but for hotel equipment the mode of ringing of the several alarm-bells simultaneously, as herein described, is recommended as preferable.

I reserve the right to claim in another application matter described herein and not now claimed.

What I claim is—

1. In a system of signals and alarms for hotels and buildings, the combination of the following-named elements, to wit: an office apparatus adapted to receive calls, one or more wires leading from said apparatus to the apartments of the hotel, batteries for charging said wire or wires, devices in each apartment adapted to transmit calls to said office, an alarm-bell in each apartment adapted to respond to alarm-signals from said office, a thermostatic

device in each apartment adapted to be released by the action of heat to transmit an alarm-signal to said office, and means at the office for transmitting alarm-signals to these several apartments, the whole arranged and operating substantially as and for the purpose set forth.

2. The combination, with an annunciator and bell located in an office or other convenient place in a hotel, with wires leading to the several rooms of the building, batteries for charging said wires, and a key at each room adapted to transmit calls to said annunciator and bell, of a thermostat in each room adapted to become released by the action of heat, to transmit an alarm-signal to the office, and an alarm apparatus in each room adapted to respond to alarm-signals from the office, and devices at the office adapted to transmit alarm-signals to the several rooms, substantially as set forth.

3. A series of wires extending from an office to several apartments of a hotel or other building, with devices for each apartment adapted to transmit electric signals to said office by a make and break of a circuit independent of the other apartments, electro-magnetic apparatus at the office for denoting from which apartment signals are sent, independent devices at said office for transmitting outgoing signals to the several apartments, and electro-magnetic apparatus in each apartment adapted to respond only to the action of heat and to signals sent from said office, and a thermostat in each room that is made operative by the action of heat upon an easily-fused metal, and adapted to transmit alarm-signals by a make and break of the circuit to said office and sound an alarm in the apartment in which said active thermostat is located, independent of other apartments, substantially as described.

4. In the equipment of a hotel-room, the combination, with a transmitting device and connected apparatus adapted to produce a definite call-signal at a remote part of the building, of an electro-magnetic alarm apparatus adapted to remain silent when said transmitting device is made operative, and a thermostat in said room adapted to make operative the signal-receiving apparatus in the re-

note part of the building, and the alarm apparatus in said room, simultaneously, when acted upon by heat, the whole arranged and operating substantially in the manner and for the purpose set forth.

55

5. The combination, with an apparatus located at a hotel-office and adapted to receive calls, with wires and batteries, and keys in the several rooms of the hotel for transmitting calls to said office, of a thermostat in each room adapted to be made operative by the action of heat to transmit an alarm-signal to said office, and an alarm apparatus in each room adapted to respond to alarm-signals from said office, and devices at said office for transmitting alarm-signals to the several rooms simultaneously, substantially as described.

65

6. The combination of the annunciator A, bell G, the wires 1 2 3, the keys P B, the bells G' G', the thermostat T, wire 4, and switching device S, for transferring the battery from the annunciator-circuits to the alarm-circuit 4, with return circuits and connections for the several parts, the whole arranged and operating substantially in the manner and for the purpose set forth.

75

7. In a combined call-bell and fire-alarm system, an office provided with apparatus adapted to receive call-signals and to transmit outgoing alarm-signals to several apartments simultaneously, one or more wires for connecting said office apparatus with the apartments of a building, devices at each apartment adapted to transmit a call-signal to said office, and an alarm apparatus at each apartment adapted to respond to signals sent from said office, and to remain silent when signals are sent from apartments to the office.

85

8. The combination, with the annunciator A, bell G, wires 1 2 3, and keys P B, for receiving and transmitting call-signals, of the alarm-bells G' G', and devices adapted to produce alarm-signals over a circuit formed in part of the circuits employed to make operative the said call-signals, and in part by a special wire 95 or conductor.
